[57] CLAIM

The ornamental design for a vehicular grill guard, as shown and described.

DESCRIPTION

FIG. 1 is a perspective view of the vehicular grill guard of our new design;

FIG. 2 is a top plan view of the vehicular grill guard of our new design;

FIG. 3 is a front elevational view thereof;

FIG. 4 is a rear elevational view thereof;

FIG. 5 is a bottom plan view thereof;

FIG. 6 is a side elevational view thereof, taken along the lines 6—6 of FIG. 3;

FIG. 7 is a side elevational view thereof, taken along the lines 7—7 of FIG. 3; and,

FIG. 8 is a perspective view of the vehicular grill guard of our new design, it being understood that the broken lines are for illustrative purposes only to illustrate the environment in which the vehicular grill guard will be used and that such broken lines form no part of the claimed design.

FIG. 1

FIG. 4

FIG. 5

FIG. 6

FIG. 7

FIG. 8
